UNITED STATES PATENT OFFICE

ROBERT D. DUNCAN, JR., OF EAST ORANGE, NEW JERSEY, ASSIGNOR TO WIRED RADIO, INC., OF NEW YORK, N. Y., A CORPORATION OF DELAWARE

MEANS FOR RECEIVING WIRED RADIO SIGNALS ON SPACE RADIORECEIVERS

Application filed June 3, 1931. Serial No. 541,770.

My invention pertains in general to electron discharge tube adapters and specifically relates to a combined tube adapter and wave filter system.

5 In my co-pending application Serial Number 431,116, filed February 25, 1930, and entitled "Electron discharge tube adapter," I have disclosed a system for employing a space radio receiving system including the usual 10 space discharge detector tube with an adapter for use interposed between the detector tube and its supporting socket for tying in a wired radio tuning system so that either space radio or wired radio signals can be detected on the 15 space radio detector tube and subsequently amplified on the space radio amplifier. It has been found, in such a system for tying in a source of wired radio signals to a space radio detector and amplifier, that the wired 20 radio carrier frequency energy is sometimes present in the audio frequency amplifier, since the wired radio carrier frequencies are much lower than the space radio frequencies. The presence of carrier in the audio system 25 of the space radio receiver may cause distortion due to the saturation of the audio frequency iron core transformer.

One of the objects of my invention consists in providing means for eliminating carrier frequency oscillations in the audio frequency amplifying system in a combined wired radio and space radio receiving system.

Another object consists in producing a combined wired radio and space radio receiving 35 system in which a low pass filter network is included in the detecting and audio frequency amplifying system.

Another object comprises providing an adapter for use interposed between a space discharge tube and a supporting socket therefor and which includes a filter network.

I accomplish the above desirable objects in a novel tube adapter having a low pass filter network incorporated therewith.

45 In the drawing accompanying and forming a part of this specification and in which like reference numerals designate corresponding parts throughout:

Fig. 1 is a diagrammatic representation of 50 a space radio receiving system having an

adapter for tying in a wired radio selective filter system to the detector and audio frequency amplifier; and

Fig. 2 is an elevation and partially sectioned view of the tube adapter and filter 55 employed in my invention.

Referring to the drawing in detail and particularly to Fig. 1, power lines 1 convey both commercial power and carrier frequency energy. The lines 1 are indicative of a wired 60 radio broadcasting system in which carrier frequency signals are impressed upon a power distribution network. A wired radio selective filter system 2 is connected to the lines 1 through capacitive couplings 3. The filter 65 system 2 consists of a network for selecting desired frequency bands of carrier frequency energy.

A high frequency energy collecting system 70 comprising an antenna 4 and ground connection 5 is connected to the input of a space radio tuning system 6. The space radio tuning system 6 comprises a suitable circuit for receiving high frequency signals of a desired frequency and may include space discharge 75 tubes for radio frequency amplification. The output of the tuning system 6 is directed through a grid leak and condenser 7 to a supporting socket 8 adapted to hold a space discharge detector tube 9. The space discharge tube 9 is provided with the usual terminal pins 10 which will fit in corresponding terminal clips 11 in the socket 8. The terminal clip 11 which is associated with the plate

or anode of the space discharge tube 9 is connected through an audio frequency transformer 12 to an audio frequency amplifier 13 and thence to any suitable translating device. A by-pass condenser 14 is provided across the primary of the transformer 12. The grid 80 leak and condenser 7 is connected, as shown, to the terminal clip 11 which is associated with the grid or control electrode of the space discharge tube 9. The other terminal clips

11 which are associated with the cathode and heater filament of the space discharge tube 9 are connected, as indicated, to ground and to a source of electrical energy 25. A source of anode voltage 30 is provided, as shown, in circuit with the terminal clip 11 which is as- 100

sociated with the anode of the space discharge tube 9. The tuning system 6, grid leak and condenser 7, socket 8, space discharge detector tube 9, and audio frequency amplifier 13 comprise a typical space radio receiving system. In the normal use of such a system the space discharge tube 9 would be inserted in the socket 8 and a suitable circuit thereby established between the output of the tuning system 6 and grid of the detector tube 9, and between the plate of the tube 9 and input of the audio amplifier 13.

However, it is especially desirable to provide means whereby wired radio signals can be made available on such a space radio receiving system. To accomplish this, according to my invention, I provide a special type of adapter which is interposed between the space discharge detector tube 9 and supporting socket 8 whereby the output of the wired radio filter system 2 can be conveniently tied into the detecting and amplifying organization of the space radio receiver without disturbing the circuit constants of the space radio receiver. This adapter 15 is essentially of low capacitance construction and includes a plurality of terminal clips 16 which are similar to the terminal clips 11 in the supporting socket 8. The adapter 15 also includes a plurality of terminal pins 17 which are similar to the terminal pins 10 found on the space discharge detector tube 9. The terminal clips 16 are adapted to retain the terminal pins 10, while the terminal pins 17 are adapted to be inserted in the terminal pins 11 of the socket 8 in place of the space discharge detector tube 9.

A switch 18 is provided within the adapter 15 for making connection with either of two terminals 19 or 20. The switch 18 is connected to the terminal pin 16 which is associated with the grid of the space discharge tube 9, while the terminal 20 is connected to the terminal pin 17 which is associated with the grid leak and condenser 7. The terminal 19 is connected through a grid leak and condenser 21 to the output of the wired radio filter system 2, the other side of which is grounded. The terminal pin 16 which is associated with the plate of the space discharge detector tube 9 is connected through inductance 22 to the terminal pin 17 which is associated with the audio frequency transformer 12. The inductance 22 is connected in parallel with two series connected capacitances 23 and 24. The capacitances 23 and 24 and the inductance 22 together comprise a filter network of the cut-off type which is adapted to attenuate all frequencies lying above a certain predetermined frequency value. This predetermined frequency value, in the present embodiment of my invention, is just below the lowest carrier frequency to be demodulated, whereby all carrier frequency energy will be attenuated by the network

22-23-24. A connection is provided between the two capacitances 23 and 24 to the terminal pin 17 and clip 16 associated with the grounded cathode of the space discharge detector tube 9. The terminal clips 16 associated with the heater filament of the space discharge tube 9 are connected to corresponding terminal pins 17 and fit into the terminal clips 11 connected to the source of electrical energy 25.

The mechanical construction of the adapter 15 will be apparent by reference to Fig. 2. It will be seen that the terminal clips 16 are mounted upon an insulating disk 26 having holes therein for receiving the terminal pins 10 of the space discharge detector tube 9. The disk 26 is disposed within a tubular shield 27. Another insulating disk 28 is provided within the tubular shield 27 and supports the terminal pins 17. The terminal pins 17 engage with the terminal clips 11 in the socket 8. The inductance 22 is mounted on the insulating disk 28 adjacent the capacitances 23 and 24. The switch 18 is also mounted upon the disk 28 and is provided with a handle which extends through an aperture in the tubular shield 27.

The switch 18 can be moved to render the detector tube 9 effective for receiving signals from either the wired radio filter system 2 or space radio tuning system 6. It will be obvious that the output from the plate of the detector tube 9 will be restricted to the desired audio frequencies due to the presence of the low pass filter system in the adapter 15. This filter system will prevent the carrier frequency current, such as received by filter system 2, from entering the primary of the transformer 12.

The system of my invention provides an efficient method for employing a source of wired radio signals with a space radio receiving system and at the same time overcoming the introduction of disturbing wired radio carrier frequencies in the space radio audio frequency organization. It will be obvious that the system of my invention possesses great commercial utility and offers many advantages in its use. By the use of my system it is possible to increase the usefulness of a space radio receiving system by tying in space radio signals without producing accompanying disturbing effects in the space radio detector and receiving system. Although I have shown a preferred embodiment of my invention I do not wish to be limited thereto except insofar as may be pointed out in the appended claims.

What I claim as new and original and desire to secure by Letters Patent of the United States is:

1. A radio receiving system, comprising, a space radio energy collecting system, a wired radio energy collecting system, a detector tube, a supporting socket for said detector

tube, an audio frequency amplifier operatively connected to said socket, an adapter interposed between said detector tube and said socket, a single pole two position switch in
5 said adapter for connecting said detector tube to said space radio energy collecting system or said wired radio energy collecting system and a filter system included in said adapter for excluding super-audible frequencies from
10 said amplifier.

2. In a combined space and wired radio receiving system, a space radio tuning system, a wired radio tuning system, a detector tube common to said tuning systems, an audio frequency amplifier common to said detector, a socket for said detector tube and an adapter interposed between said detector tube and said socket containing a single pole two-position switch for connecting said detector tube
15 with either said wired radio tuning system or said space radio tuning system selectively and a filter system in said adapter for attenuating super-audible frequencies and preventing such frequencies from entering said audio
20 frequency amplifier.

3. A combined space and wired radio receiver comprising a space radio tuning system, a wired radio tuning system, a thermionic detector tube common to said tuning systems, a socket therefor, an audio frequency amplifier operatively connected to said socket and an adapter interposed between said socket and said detector tube and containing a single pole two-position switch for connecting said wired radio tuning system or said space radio tuning system to the grid of said detector tube and a filter system included in
35 said adapter for preventing super-audible frequencies from entering said audio amplifier.
